S. Hunt,

Harness Saddle.

No 11262.

Patented July 11, 1854.

UNITED STATES PATENT OFFICE.

SAMUEL HUNT, OF BALTIMORE, MARYLAND.

APPARATUS FOR DETACHING HARNESS FROM HORSES.

Specification of Letters Patent No. 11,262, dated July 11, 1854.

To all whom it may concern:

Be it known that I, SAMUEL HUNT, of Baltimore city, in the State of Maryland, have invented certain new improvements 5 upon the invention for detaching harness from horses, for which Letters Patent were granted to George Yellott on the 15th day of June, in the year 1852; and I do hereby declare that the following is a full and exact 10 description of my said improvements, reference being had to the accompanying drawings and the letters and figures of reference marked thereon.

The nature of my invention consists, first, 15 in fastening together the two sections of the saddle-tree by means of a spiral spring attached to a metal shaft running through a tongue and groove near the front of the saddle tree, and by another tongue and 20 groove at the back of the tree, the whole concealed in the interior of the saddle tree so as not to be visible when the two sections are joined together; second, in arranging 25 two turrets on the top of the front of the saddle tree to accommodate the bridle rein, driving reins and detaching cord, and in such manner that said turrets apparently 30 make one when the two sections of the saddle tree are joined, but fall apart from each other and the tree as soon as its two sections are disunited.

To enable others skilled in the art to make and use my invention, I will proceed to describe its construction and operation.

35 The accompanying Drawing A represents the two sections of the saddle tree and turrets united. Drawings B, C, D and E represent the two sections of the saddle tree and turrets separated. Drawing F represents 40 the shape of each of the turrets.

Figure 1 in Drawing B represents the spiral spring and metal shaft, by means of which the two sections of the saddle tree are held together or disunited at pleasure, said 45 metal shaft having a handle projecting behind the saddle tree on one end and being beveled at the other end.

Fig. 2 in Drawing B represents the handle of the metal shaft at the back of the 50 saddle tree; and Fig. 3 the cord attached thereto, by which cord when pulled by the driver the harness can be detached. Fig. 4 in Drawing A represents another view of the handle of the metal shaft.

55 Fig. 5 in Drawing C represents the tongue

arranged near the front of one section of the saddle tree; and Fig. 6 in Drawing B, represents the corresponding groove in the other section into which this tongue is designed to fit, and through this tongue the 60 beveled end of the metal shaft passes when the sections are joined. Fig. 8 in Drawing B represents another tongue of a different shape in the other section of the saddle tree and projecting upward at its upper end to 65 a point.

Fig. 7 in Drawing C represents a groove into which the tongue represented by Fig. 8 closely fits when the two sections of the saddle tree are united. The metal shaft does 70 not pass through this tongue.

Figs. 9 and 10 in Drawings B and C represent grooves in the top of the front of each section of the saddle tree into which grooves the ends of the turrets are to be 75 fixed when the two sections of the saddle tree are joined together.

Figs. 11 and 12 in Drawing A represent the rings at the ends of the turrets through which the driving reins pass.

Fig. 13 in Drawing A represents the base 80 of the turrets around which the bridle rein will pass when the sections of the saddle tree are joined.

Fig. 14 in Drawing A represents a ring 85 in the middle of the turrets at top, formed by uniting them together, through which ring will pass the detaching cord attached to the handle of the saddle tree shaft and intended to be pulled forcibly by the driver 90 when desiring to detach the harness from the horse.

What I claim as my invention, and desire to secure by Letters Patent, is—

Uniting the two sections of a saddle tree 95 by a tongue projection from one section and fastened in a corresponding groove in the other, by a metal shaft and spiral spring, the whole being entirely concealed from view, and arranged and operating substantially as above set forth and described. Also, arranging a set of turrets in two sections, each fitting into a dove-tailed groove 100 in the top of the front of one section of the saddle tree, arranged and operating substantially as above set forth and described. 105

SAML. HUNT.
